UNITED STATES PATENT OFFICE.

JOHN ZELLWEGER, OF CHICAGO, ILLINOIS.

RECUPERATOR-FURNACE.

SPECIFICATION forming part of Letters Patent No. 279,475, dated June 12, 1883.

Application filed February 2, 1883. (No model.)

To all whom it may concern:

Be it known that I, JOHN ZELLWEGER, a citizen of the United States, residing at Chicago, in the county of Cook and State of Illinois, have invented certain new and useful Improvements in Recuperator-Furnaces; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

The present invention relates to the class of recuperators which employs separate fire-flues and air-flues. The most effective method of heating air and gases is by direct contact with hot bodies, as radiant heat has little or no effect.

The characteristic feature of recuperators of this class heretofore built is that the air is heated by contact with one side of the fire-walls, which are heated on their other side directly by fire-gases, steam, &c. From this follows another characteristic feature common to all regenerators heretofore built with a number of parallel flues, which is, that none utilize the heat that radiates from wall to wall through the air between those flues. In the recuperators of a gas-furnace, for example, built with several parallel fire-flues and air-spaces between them, the heat that radiates from the fire-walls is either received by other fire-walls or by the outside walls of the recuperator; but since in the first case each fire-wall that radiates heat to another one opposite it receives an equal amount of radiant heat from that wall, it follows that the temperature of both is unchanged, as if no radiation had taken place; and, further, that only a small amount of radiant heat is transferred to the air. The heat radiated from a fire-wall to the circumference wall of the recuperator is there partly lost by conduction through the wall to the outside. Another defect of the recuperators in common use, especially in connection with gas-furnaces, is that they fail to fully develop the ascending force of the hot air in proportion to the height of the apparatus. In some recuperators because of the great length of the horizontal air-flues, or

the zigzag course of the air currents, or because of a forced downward flow of heated air. In others because the air-spaces occupy but a part of the height of the recuperator and are obstructed by numerous projections or by hollow tie-bricks connecting two neighboring fire-flues. A third defect of existing recuperators heated by fire-gases is that the fire-walls are connected or joined to the outside wall, which brings the fire-gases in contact with that wall, causing damage to the outside wall and loss of heat.

My improved recuperator utilizes effectively all the heat conducted through its fire-walls, and also the maximum ascending force of the hot-air column, due to the height of the recuperator, and it does not suffer from unequal heating of its walls, while the loss of heat outward is reduced to a minimum.

I construct my air-heating apparatus or regenerator as an air-chamber containing two or more vertical isolated fire-flues, with intermediate walls or piers interposed between all the fire-flues. The fire-flues, which are separated from the outside wall by air-spaces, extend from the floor of the air-chamber to or near to the cap of it, and have generally a narrow but long horizontal section, extending nearly over the entire length or the width of the air-chamber. By this arrangement the circulation of the air and gases is the least obstructed, and the fire-flues are free to expand and contract under the action of the heat. The intermediate walls or piers placed in the air-space between two fire-walls represent the most important part of the improvement. They intercept the heat radiating from the fire-walls and then offer it to the air coming in contact with them. These intermediate walls may or may not connect with the outside wall, but they generally extend from the floor of the air-chamber to the top, supporting wholly or in part the cap of the air-chamber. These intermediate walls also give side support to the light fire-flue walls. In the case of the length of the horizontal section of the fire-flues being divided into two or more parts a second set of intermediate walls or pillars may be placed between those parts and at right angles to the first ones, dividing the horizontal section of the air-chamber into a number of

sections, each containing a fire-flue. I also place these intermediate walls or pillars between the two wings of U-shaped sections of fire-flues and into the middle of ring-shaped sections. The intermediate walls need not be straight, but may follow the windings of the fire-wall. This principle of placing intermediate walls in the air-space between two fire-walls or heating-surfaces, or between two opposite parts of one fire-wall or heating-surface, is applicable to all kinds of recuperators or air-heating apparatuses, and not only to vertical walls, but also to horizontal ones, by interposing horizontal plates to intercept the heat-rays. Walls, pillars, and plates may have plain surfaces, or may have projections or ribs on them. They may be made of clay or metal or of both combined. Air-flues in horizontal or vertical position and surrounded by fire-gases may be divided into two sections by a partition through them. In my recuperator the fire-gases enter the fire-flues through fire-ports at or near the top, either directly from the furnace-chamber or from a horizontal distributing fire-flue, and escape at the bottom into a horizontal collecting fire-flue that leads to the stack. The air enters the air-chamber at the bottom and escapes at the top through one or more openings in the sides or cap of the air-chamber. Sometimes I make a distributing air-flue at the bottom and a collecting air-flue at the top, passing through fire-flues and intermediate walls.

For the purpose of cleaning the fire-flues I provide openings through the outside wall of the air-chamber leading to the top and to the bottom of the fire-flues. For the purpose of facilitating repairs of the fire-flues I support the roof of the air-chamber by the intermediate or partition walls only. The partition-walls may be perforated to facilitate air-circulation.

In the accompanying drawings, Figure 1 is a perspective view of a recuperator embodying my invention with portions broken away to show the arrangement of flues and walls. Fig. 2 is a similar view of a simpler form of recuperator, also constructed according to my invention. Fig. 3 is a vertical cross-section in the plane X of Fig. 1. Fig. 4 is a vertical longitudinal section taken half through a fire-flue and half through an air-flue, as indicated by the line y y' of Fig. 6. Fig. 5 is a horizontal section on the broken line z z' z'' of Fig. 3. Fig. 6 is a horizontal section on the line v v' of Fig. 4. Figs. 7 to 10, inclusive, are sections illustrating the construction of the regenerator shown by Fig. 2, Fig. 7 being a vertical cross-section in the plane w, Fig. 8 a vertical longitudinal section in the plane w', Fig. 9 a vertical cross-section on the line w', and Fig. 10 a horizontal section on the line w'.

The gases and products of combustion from the furnace are admitted through the fire-ports or openings A, and pass out through the outlet C to the chimney,

B is the inlet and D the outlet for the air,

the courses of the currents through the air and fire flues being indicated by arrows.

The fire-flues E receive the products of combustion at the top from the fire-ports A and deliver them at the bottom to the collecting fire-flue C, passing transversely through the fire-flues E. The compact arrangement of the distributing air-flue that also passes transversely through the air-spaces, and of the collecting fire-flue of the first form of regenerator is clearly shown by Figs. 1, 3, and 4, both connecting at the bottom with the air-flues F and fire-flues E, respectively. The air passes from the distributing-flue B through the ports b into the air-flues F, and the gases and products of combustion pass from the fire-flues E under the partition e through the ports e' into the collecting fire-flue C.

The letter G indicates the partition-walls placed between the fire-flues. Openings H and I into the fire-flues at the top and bottom, respectively, are provided for the purpose of cleaning the flues. These are generally closed by plugs. The floors of the openings H are not level, and slope from the inside out, or are provided with ledges h, just inside the bottom of the fire-ports A, to catch any molten matter that may drop through the fire-ports and prevent it from getting into the flues.

The fire-ports A may be connected by a horizontal distributing-flue, which can be made to serve as a clay or glass pocket, instead of each communicating with a single fire-flue, as shown. The walls of the fire-flues are in the first form of regenerator detached from the external walls at the ends and top, except at the corners, where connection is made with the fire-ports. In the second form of recuperator they extend from the bottom to the top, but are detached at the ends.

Sometimes it is necessary to place a gas-flue inside of a recuperator, in which case the fire-flue walls and the intermediate walls can be used to brace the walls of the gas-flue by joining them directly to the brick-work of said flue.

This recuperator plan can also be used as air-heating apparatus for dry-kilns, malt-kilns, &c., when the distributing fire-flues are built in connection with hearths for the combustion of solid fuel, or with a burner for the combustion of liquid or gaseous fuel. For such cases the air-outlets may be located in the cap of the apparatus and the apparatus itself at the bottom of the drying-room.

What I claim as my invention, and desire to secure by Letters Patent, is—

1. An air-heating apparatus having intermediate walls, pillars, or plates in the air-space between two fire-walls or heating-surfaces, substantially as and for the purpose set forth.

2. A recuperator consisting of an air-chamber with fire-flues reaching from the floor of said chamber nearly to the top and detached from the external walls of the regenerator at

the ends, sides, and top, substantially as and for the purpose set forth.

3. A recuperator consisting of an air-chamber with fire-flues reaching from the floor of said chamber to the top and attached at the corners to the external walls of the regenerator, substantially as herein set forth.

4. A recuperator having fire-flues with intermediate walls or piers supporting the roof 10 of the air-chamber, substantially as and for the purpose set forth.

5. A recuperator having alternate fire and air flues, and a collecting fire-flue and distributing air-flue, which pass through the fire-flues and air-spaces, and partition-walls when used, and communicate, respectively, with the 15

fire and air flues, substantially as and for the purpose set forth.

6. A recuperator having collecting and distributing fire and air flues both at the top and 20 bottom, which pass through the fire-flues, air-spaces, and partition-walls when used, and communicate, respectively, with the fire and air flues, substantially as and for the purpose set forth.

25 In testimony whereof I affix my signature in presence of two witnesses.

JOHN ZELLWEGER.
